(57) **CLAIM**

The ornamental design for a liquid dispenser, as shown and described.

DESCRIPTION

FIG. 1 is a perspective view showing our new design for a liquid dispenser.

FIG. 2 is a right side view thereof.

FIG. 3 is a left side view thereof.

FIG. 4 is a front view thereof.

FIG. 5 is a back view thereof.

FIG. 6 is a top view thereof.

FIG. 7 is a bottom view thereof; and,

FIG. 8 is a perspective view showing the cap, bottle and unclaimed sponge in a separated state.

The broken lines showing a sponge and its association with the dispenser in FIG. 8 form no part of the claimed design, but are included for the purpose of illustrating the nature and intended use thereof.

The broken lines showing the nozzle outlet in FIGS. 1, 4 and 8 and the sponge in FIG. 8 are for illustrative purposes only; and form no part of the claimed design. The broken line in FIG. 7 likewise forms no part of the claim, but is provided to indicate the boundary of the unclaimed region of the bottom end.
